CLAIM

The ornamental design for a flip ring, as shown.

DESCRIPTION

FIG. 1 is a perspective view showing the front, top and right sides of one embodiment of the flip ring;

FIG. 2 is a right side elevation view of the flip ring of FIG. 1, the left side elevation view being a mirror image thereof;

FIG. 3 is a front elevation view of the flip ring of FIGS. 1-2, the rear elevation view being a mirror image thereof;

FIG. 4 is a top plan view of the flip ring of FIGS. 1-3;

FIG. 5 is a bottom plan view of the flip ring FIGS. 1-4;

FIG. 6 is a perspective view showing the front, top and right sides of another embodiment of the flip ring;

FIG. 7 is a right side elevation view of the flip ring of FIG. 6, the left side elevation view being a mirror image thereof;

FIG. 8 is a front elevation view of the flip ring of FIGS. 6-7, the rear elevation view being a mirror image thereof;

FIG. 9 is a top plan view of the flip ring of FIGS. 6-8;

FIG. 10 is a bottom plan view of the flip ring FIGS. 6-9;

FIG. 11 is a perspective view showing the front, top and right sides of another embodiment of the flip ring;

FIG. 12 is a right side elevation view of the flip ring of FIG. 11, the left side elevation view being a mirror image thereof;

FIG. 13 is a front elevation view of the flip ring of FIGS. 11-12, the rear elevation view being a mirror image thereof;

FIG. 14 is a top plan view of the flip ring of FIGS. 11-13; and,

FIG. 15 is a bottom plan view of the flip ring of FIGS. 11-14.
